INCENSE BURNER

Harry O. White, Jr., Sebastopol, Calif.

Application October 4, 1937, Serial No. 167,107

2 Claims. (Cl. 21—116)

This invention relates generally to an incense burner and in particular relates to a combination ornamental novelty and incense burner.

The principal object of my invention is to provide an incense burner arranged in combination with electric lighting means and an enclosing hood designed to simulate the cone of a volcano or the like whereby, upon illumination of the incense smoke emanating from the hood, a very realistic and ornamental effect is obtained.

A further object of my invention is to provide an air supply or feed conduit arranged to feed air in ample quantity directly to the burning incense beneath the hood of the device; such air feed being selectively controlled by an adjustable damper.

A further object of the invention is to produce a simple and inexpensive device and yet one which will be exceedingly effective for the purpose for which it is designed.

These objects I accomplish by means of such structure and relative arrangements of parts as will fully appear by a perusal of the following specification and claims.

25 The figure of the drawing is a sectional elevation of the device.

Referring now more particularly to the characters of reference on the drawing, the numeral 1 indicates a hollow substantially frusto-conical hood having a top opening 2; the exterior of the hood being formed, and finished, in the present instance, to simulate the cone of a volcano. The hood 1 removably rests on a base 3, the lower edge of the hood having a downwardly extending circular flange 4 which closely engages in a complementary groove 5 in the base. This flange and groove arrangement prevents undesired air leakage into hood 1, as well as serving as a locator. The hood 1 and base 3 are preferably made of initially plastic material molded to shape. A cup 6 is formed in the base at a point in substantial alignment with opening 2, such cup being adapted to receive and support a burnable incense element 7. An electric light socket 8 is mounted on the base to one side of cup 6 and is supplied with current by means of a two wire cord 9 which enters the base on one side and is embedded therein to a point adjacent the socket.

50 A light bulb 10, preferably of flame color, is threaded into the socket and a so called "flasher button" 11 is disposed in the socket between the end terminal of the bulb and bottom terminal of the socket. This "flasher button" produces intermittent illumination of the bulb and for the reason hereinafter set forth.

An air feed conduit 12 is embedded in the base and is provided with an internal upstanding air feed neck 13 which terminates substantially horizontal and on the opposite side of cup 6 from socket 8. This neck 13 terminates at such point above the cup and slightly to the side thereof so that the air from said neck will flow directly across the incense element 7. The outer end of conduit 12 extends out of the base and is provided with a manually adjustable closure member or 10 damper 14.

In use, the above described device functions in the following manner:

The hood 1 is removed and an incense element 7 placed in cup 6 and ignited. The hood is then replaced on the base and light bulb 10 illuminated, the bulb flashing on and off due to the intermittent make and break of the circuit by "flasher button" 11. Thus, as smoke from the burning incense emanates from top opening 2 in the hood, such smoke is illuminated intermittently by the flame colored light bulb, producing a unique representation of an erupting volcano.

The provision of the air feed conduit 12 with the internal air feed neck 13 and adjustable 25 damper, assures proper combustion of the burning incense element. As the incense receiving cup is disposed intermediate air feed neck 13 and bulb 10, air from the neck will be drawn, by the natural draft created by the heat of bulb 10, from the neck and fed directly across the burning incense element. To prevent excessive and too rapid burning of the incense, the volume of air passing through conduit 12 may be controlled by 30 damper 14.

35 Though in the present embodiment of my invention the exterior surface of the hood represents a volcano, such representation may be varied if desired in order to produce other novel effects.

40 From the foregoing description it will be readily seen that I have produced such a device as substantially fulfills the objects of the invention as set forth herein.

45 While this specification sets forth in detail the present and preferred construction of the device, still in practice such deviations from such detail may be resorted to as do not form a departure from the spirit of the invention as defined by the appended claims.

50 Having thus described my invention, what I claim as new and useful and desire to secure by Letters Patent is:

55 1. An incense burner comprising a base, a hood mounted on the base, said hood having a top

opening therein, an incense receiving cup on the base, an electric bulb and socket unit mounted on the base to one side of the cup, a conduit extending from exteriorly of the hood to a point within the hood adjacent the cup and on the opposite side, the inner end of said conduit being arranged to feed air across the cup.

2. An incense burner comprising a base, a hood mounted on the base, said hood having a top opening therein, an incense receiving cup on the

base, an electric bulb and socket unit mounted on the base to one side of the cup, a conduit extending from exteriorly of the hood to a point within the hood, the inner end portion of the conduit opening toward the cup and being substantially horizontal, said portion being disposed above the cup and to the side thereof opposite the bulb and socket unit.
